UNITED STATES PATENT OFFICE.

HARRY A. ATWATER, OF KANSAS CITY, MISSOURI, ASSIGNOR TO COMBUSTION EQUIPMENT COMPANY, OF KANSAS CITY, MISSOURI, A PARTNERSHIP COMPOSED OF A. W. MACKIE, D. J. MACKIE, R. V. DOWNS, AND HARRY A. ATWATER.

OIL BURNER.

Application filed February 16, 1925. Serial No. 9,599.

The present invention relates to liquid or gaseous fuel burners, and aims to provide a novel and improved burner construction in which provision is made for efficiently regulating the air supply to the space into which the fuel mixture is discharged and where the ignition of the fuel begins to take place.

Accordingly, I have devised an improved type of burner of this character in which means are provided for shielding the space immediately surrounding the fuel discharge point, together with a device for regulating the movement of air to and from this space during the burner's operation.

It is also sought to embody the invention in a construction in which a fuel atomizing medium is used in connection with the feeding of the fuel, and aims to provide a hood member carried by the device which regulates the flow of said atomizing medium, and also an air regulating device which controls the flow of air through the space within said hood member.

With these general objects in view, the invention will now be described by reference to the accompanying drawing illustrating one form of construction which I have devised for embodying the proposed improvements, after which those features and combinations deemed to be novel will be particularly set forth and claimed.

In the drawing—

Figure 1 is a side elevation showing an oil burner constructed in accordance with the present invention;

Figure 2 is a longitudinal sectional view, representing a section taken on the lines II—II of Figure 1; and

Figure 3 is an end face view of the burner.

In certain industrial operations, and particularly in the burning of refractory or clay products in kilns, the changing temperature conditions involved require such regulation or control of the heat generating plant that oil burning devices have not heretofore been able to operate with full efficiency. In such industrial plants, the rate of oil consumption varies over a wide range on account of the relatively low temperature at which the clay burning operation is started, and the greatly increased temperature attained toward the end of this operation. These and other factors necessarily

involved in such operating conditions require an oil burner to undergo adjustments of its operation that are not necessary for many other industrial uses.

With the commercial grade of oil usually employed with burners in such plants, it is necessary to use an atomizing medium, such as steam or compressed air, to effect proper atomization of the fuel and formation of an efficient combustible mixture. But even with the most careful regulation of the flow of both the fuel and its atomizing medium in this type of burner, under low flame conditions the flame is usually characterized by an intermittent popping action, i. e., an intermittent extinguishing and reigniting of the flame, on account of the low temperature existing in the combustion chamber of the fire box, and the difficulty of avoiding entirely the effect of the chilling action of the air required for combustion purposes. Obviously, the mere variation of the size of the orifices of the fuel feed and the atomizing medium cannot have any material effect on the ignition temperature under extremely low flame conditions, and it is such factors as these which are largely responsible for the inefficient combustion at this stage of operation.

Now while it is not possible to overcome this difficulty by further regulation of the feed of the fuel or its atomizing medium, a corrective action can be obtained by eliminating as far as possible the chilling action of the air relied upon to support combustion at the fuel discharge point. Accordingly, in the present design of burner I employ a hood device for shielding the ignition zone around this point, and further provide means of regulation for the movement of air to and from the same.

Referring now to the drawing in detail, this illustrates a burner member comprising a casting 4 having a central fuel passage 5 through which liquid fuel such as oil is conducted by means of a pipe 6, and surrounding this passage 5 is an annular passage 7 through which any suitable atomizing medium such as steam or air under pressure is conducted by means of a supply pipe 8. At the discharge end of the passage 5 is fitted a nozzle tip element 9 having the discharge orifice 10 through which the discharge of

fuel is regulated by the point 11 of a needle valve, the stem 12 of which extends centrally through the passage 5 and through the packing nut 14, the outer end of the stem being fitted with the usual operating handle 15.

The air space immediately surrounding the discharge orifice 10 is shielded by a conical or flaring air hood member 16 having a cylindrical casing portion 17 of a diameter 10 slightly greater than the adjacent end of the burner casting 4, with which it is engaged by means of a screw thread as indicated at 18 (Figure 2). This combined hood member and casing portion is furthermore provided with a cone-shaped partition 20 designed to close up the outer end of the annular passage 7, and this partition is formed with a central opening 22 surrounding the tip of the nozzle 9, and thus providing an annular discharge orifice for the atomizing medium, which orifice obviously is regulated by the adjustment of the combined hood member 16 and its casing portion 17 upon the burner 4 through the medium of the 25 thread 18.

Upon the hood member 16 is mounted a similarly shaped shutter member 24 having a cylindrical portion 25 fitted upon the casing portion 17 of the hood member, the hood and 30 shutter member being formed with registerable openings 26 for the purpose of admitting air to the space within the hood member, and obviously the shutter being rotatably mounted upon the hood member, the 35 passages thus afforded for the movement of air can be increased or diminished to suit the operating condition of the burner. A cylindrical portion 25 is provided with a set screw 27 by which the shutter member may 40 be clamped after adjustment. Suitable lugs 28 may be formed upon the outer margins of the hood and shutter members for convenient engagement by means of a tool in effecting the adjustment of said members 45 from time to time.

Previous efforts have been made to improve the burner construction somewhat after this fashion, as by making use of a form of hood, but if this were made too 50 large it would burn out too rapidly and also drive the incoming air too far away from the burning fuel body, thus slowing down the rate of combustion; but if made too small, any beneficial effect of the hood would 55 be barely noticeable. The present construction aims to embody a combination of the features necessary for correcting the various operating difficulties and providing a flexibility lacking in previous constructions. As 60 will be seen, the improved burner is of the outside mixing type (that is, the main supply of air supporting combustion is supplied outside the fuel passage 5). The atomizing medium issues in a stream immediately 65 surrounding the cone of oil issuing from the

central orifice 10, the atomization being effected after leaving the burner tip proper. By virtue of the method of mounting the hood member and its casing portion 17 adjustably upon the burner casting, the size of 70 the discharge orifice of the atomizing medium may be readily regulated by simply rotating said hood member, and since the flow of fuel may be regulated by merely turning the handle 15, it is possible to secure 75 the most efficient rate of feed of both oil and atomizing medium in accordance with the desired rate of oil consumption.

The efficiency of a hood member as a means of protecting a low fire from the chilling effect of inflowing air required for combustion is unquestioned, but means should be provided for regulating such air movement and in the improved construction this is done by the regulation 80 of the shutter member 24 and varying the size of air passages through the openings 26. By this means it is possible to prevent too great a movement of air through the space directly surrounding the orifices 85 10 and 22, thereby greatly aiding in ignition and in securing a more complete flame propagation. Again, when operating under high flame conditions, at which time the high temperature attained reduces the necessity 90 for the shielding function of a hood, the air openings 26 may readily be regulated for obtaining the proper amount of air supply in this space immediately around the orifices 10 and 22. The provision of this air shutter and the adjustable openings 26 furthermore eliminates the tendency of the hood structure to burn away under high flame conditions, which constituted one objection to the solid hood structure of previous burner 95 types, with their absence of more thorough and effective air cooling.

It is obvious also that the regulation of either the rate of oil feed or the flow of the atomizing medium may be carried out separately and independently, while the adjustment of the hood for varying the flow of the atomizing medium may be attended to without any change in the size of the shutter openings, the regulation of which may thereafter be attended to without affecting any of the other adjustments.

It is thus apparent that I have devised a practical and efficient construction for carrying out the desired objects of the invention, including the protection of a low burner flame from the chilling action of air contacting with the oil jet in the ignition zone, and the regulation of the volume of air admitted to this zone during high flame 105 periods when a greatly increased air supply and more intimate air contact are required. While I have illustrated and described what I now regard as the preferred form of construction, I desire to reserve the right to 110 115 120 125 130

make all such changes and modifications as may fairly fall within the scope of the appended claim.

What I claim:

- 5 An oil burner having a fuel feeding passage provided with a discharge orifice, said burner also having a passage for feeding fluid under pressure to the exterior of said orifice, an air hood member having a casting portion adjustably mounted on said burner and formed with an inwardly projecting nozzle portion extending across said fluid pressure passage and provided with an
- 10

orifice surrounding said fuel orifice, whereby the adjustment of said hood member regulates the rate of flow of said fluid under pressure past said fuel orifice, said hood member having openings for the discharge of air to and from the space immediately surrounding said orifices, and a shutter member carried by said hood member for regulating the movement of air through said openings.

In witness whereof I hereunto affix my signature.

HARRY A. ATWATER.
